SNOWMOBILE

Kenji Ekuan, Tokyo, Japan, assignor to Yamaha
Hatsudoki Kabushiki Kaisha (Yamaha Motor Co.,
Ltd.), Nakajo, Hamakita-shi, Shizuoka-ken, Japan,
a corporation of Japan

Filed Dec. 10, 1968, Ser. No. 14,864

Claims priority, application Japan June 24, 1968

Term of patent 14 years

Int. Cl. D12—13

U.S. Cl. D14—24

FIG. 4.

FIG. 5.

FIG. 6.

FIG. 1 is a perspective view of a snowmobile showing my new design;

FIG. 2 is a front elevational view to a reduced scale from the showing of FIG. 1;

FIG. 3 is a rear elevational view;

FIG. 4 is a top plan view;

FIG. 5 is a left side elevational view; and

FIG. 6 is a right side elevational view.

I claim:

The ornamental design for a snowmobile, as shown.
